UNITED STATES PATENT OFFICE.

OTTO H. BENKE, OF STAMFORD, CONNECTICUT, ASSIGNOR TO THE YALE & TOWNE MANUFACTURING COMPANY, OF STAMFORD, CONNECTICUT.

LOCK.

Application filed August 14, 1923. Serial No. 657,278.

To all whom it may concern:

Be it known that I, OTTO H. BENKE, a citizen of the United States, and a resident of Stamford, in the county of Fairfield and 5 State of Connecticut, have invented certain new and useful Improvements in Locks; and I do hereby declare the following to be a full, clear, and exact description of the invention, such as will enable others skilled 10 in the art to which it appertains to make and use the same.

This invention relates to improvements in locks and more particularly to those of the "rim" type and embodying a cylinder lock,— 15 one object of the invention being to provide means whereby the bolt operating cam will be released from its mounting in the event that the cylinder lock be wrenched from its normal position.

With this object in view, the invention consists in certain novel features of construction as will hereinafter be more fully described and pointed out in the claim:

In the accompanying drawings,—

Figure 1 is a face view of a cover plate showing an application of the invention.

Figure 2 is a sectional view on the line 2—2 of Figure 1, and

Figure 3 is a sectional view on the line 30 3—3 of Figure 1.

A sheet metal cover plate is illustrated at 1 and is provided with holes 2 for the accommodation of bolts for securing a cylinder lock in place. A plate 3 is mounted 35 on the cover plate 1 and is secured thereto by means of rivets 4, the ends of which are but slightly upset so that upon the application of a pulling or wrenching force, said plate 3 may become removed from the cover

plate. A roll back 5 is mounted in the cover 40 plate and also in the plate 3 and one end portion of this roll back passes through a suitable hole in a roll back cam or bolt operating member 6 and its free end is slightly upset as at 7. The plate 3 is provided with 45 holes (two or more) to align with holes 2 in the cover plate and the last mentioned holes are sufficiently large to permit the passage of the heads of the securing bolts so that said heads may bear directly against 50 the plate 3.

With my improvements, if an attempt be made to wrench or pull the cylinder lock from the door, the plate 3 would be pulled away from the cover plate and the roll back 55 or thimble 5 would be stripped from the roll back cam, thus releasing the latter and permitting it to drop and be, therefore, rendered inoperable to retract the bolt.

Having fully described my invention 60 what I claim as new and desire to secure by Letters-Patent, is:

The combination with the cover plate of a rim lock, of a plate removably secured to said cover plate, a roll back mounted in said 65 plate, a roll back cam removably secured to said roll back, said plates having aligning bolt holes, the bolt holes in the cover plate being sufficiently large to permit the heads of cylinder securing bolts to seat against 70 the removable plate.

In testimony whereof, I have signed this specification in the presence of two subscribing witnesses.

OTTO H. BENKE.

Witnesses:

HARRY N. SMITH,
CHARLES A. BERRY.
